UNITED STATES PATENT OFFICE

HENRY D. LEE, OF BERKELEY, CALIFORNIA, ASSIGNOR TO THE ASHBY FURNITURE COMPANY, INCORPORATED, OF BERKELEY, CALIFORNIA, A CORPORATION OF CALIFORNIA

DESIGN FOR A SOFA

Application filed April 4, 1931. Serial No. 39,365. Term of patent 7 years.

To all whom it may concern:

Be it known that I, HENRY D. LEE, a citizen of the United States, and a resident of the city of Berkeley, county of Alameda, State of California, have invented a new, original, and ornamental Design for Sofas, of which the following is a specification, reference being had to the accompanying drawings, forming part thereof.

I claim:

The ornamental design for a sofa, substantially as shown.

In testimony whereof, I have hereunto set my hand.

HENRY D. LEE.
